CAR SIDE CONSTRUCTION.
APPLICATION FILED JUNE 10, 1911.

Patented Jan. 12, 1915.

2 SHEETS—SHEET 2.

UNITED STATES PATENT OFFICE.

CHARLES A. LINDSTRÖM, OF PITTSBURGH, PENNSYLVANIA, ASSIGNOR TO PRERESSED STEEL CAR COMPANY, OF PITTSBURGH, PENNSYLVANIA, A CORPORATION OF NEW JERSEY.

CAR SIDE CONSTRUCTION.

1,124,479.

Specification of Letters Patent. Patented Jan. 12, 1915.

Application filed June 10, 1911. Serial No. 632,416.

To all whom it may concern:

Be it known that I, CHARLES A. LINDSTRÖM, a citizen of the United States, residing at No. 138 Stratford avenue, Pittsburgh, E. E., in the county of Allegheny and State of Pennsylvania, have invented certain new and useful Improvements in Car Side Construction, of which the following is a specification.

10 An object of the present invention is to provide an improved form of door and side construction for that type of bottom dump car generally known as an "ore car", such as that described in my pending applications for United States patents, Serial Nos. 563,479 and 599,507, in which the lading is discharged through the central portion of the car bottom.

20 The tendency of ore to arch or bridge over the discharge opening in the bottom of the car has already been referred to in my pending applications above referred to, and it has been found in practice that this tendency of the lading to bridge or arch, causes 25 a portion of the ore to stick or lodge in the angular portion of the drop door illustrated in the drawings of said applications. The amount of ore which sticks in the angular portion of the door varies according to the 30 natural character of the ore itself, and according to the quantity of moisture contained in the ore, which together with the jolting and jarring inherent in transportation of ore in railway cars, increases the 35 tendency of the ore to stick and cake, and as a result of which special means have to be used to dislodge such ore from the drop door when the major portion of the ore contained in the car has been dumped.

40 It will be readily understood, from an inspection of Figure 2 of the drawings, that the advantage of the L form of doors shown therein, resides in the fact that during the opening movement of the doors, the whole 45 of the lower inclined portion of the doors moves downwardly away from the load to an extent which is greatest at the edges of the doors nearest to the longitudinal center line of the car, and decreasing somewhat toward the angular portions of the doors nearest the vertical plane of the car side, the result of such movement of the doors being, 50 that the support afforded to the lading by

the doors is entirely removed when the doors are opened, this permitting a free discharge 55 of the lading.

A specific object of the present invention is to provide such a construction, that, when the dump doors are opened, any ore having a tendency to stick or adhere to the angular portion of the doors, as shown in my pending applications hereinbefore referred to, will be automatically dislodged, without having to resort to the use of bars, shovels, or other objectionable means, and without 65 the use of any manual labor beyond that necessary to operate the doors in opening or closing them.

A side construction having the above objects and advantages is hereinafter described 70 in this specification and shown in the accompanying drawings, in which like reference characters refer to like parts throughout, and in which:

Fig. 1 is a side elevation of an ore car 75 provided with my improved side construction; Fig. 2 is a vertical sectional view on line 2-2, Fig. 1, drawn to an enlarged scale, and Figs. 3 and 4 are similar part sectional views showing modifications in the construction of the doors.

Referring now in detail to the drawings, in which the car body is represented as being V-shaped in longitudinal section by reason of its being provided with floor sheets 85 sloping downwardly to the discharge opening of the car, and in which the two lower edges of the sloping floor sheets and the two sides of the car, which sides are bent inwardly at their portions adjacent to the side 90 sills and then extend downwardly toward the doors, define the central discharge opening in the car bottom.

The car comprises body 1, sloping floor sheet 2, side sheets 3, draft sills 4, and 95 bolsters 5. The central discharge opening is closed by doors 6, which doors 6, are hinged at 7 to the triangular side sheet supporting members 14, the free edges of the doors meeting in a line extending longitudinally at the center of the width of the car. For the purpose of closing the doors any suitable mechanism, such as that described in my pending applications above referred to, may be employed.

The doors 6 are shown of a modified L

shape in cross section, and for the purpose of dislodging any lading which may cake or stick on the bent portion 8 of the door, the side sheet 3 is extended downwardly at 9, 5 below the side sill to a point 10, thus forming a hopper sheet, the lower edge 10 of said extension being in close proximity to the inner surface of the bent portion of the door, when in closed position. To prevent distortion 10 of the extension 9 of the side sheet 3 and its lower edge 10, due to pressure of the lading or other causes, a reinforcing member 11, is secured to the lower edge 10 of said sheet. In the drawings such reinforcing member is shown as being of channel section, but may be made of any other suitable section or form, and may be located on either the inner or outer sides of the side sheet extension, or on both sides. The ends 15 12 of the side sheet extension, where they contact with the sloping end floor sheets 2, are secured thereto by rivets 13, thus increasing the rigidity of said extension of the side sheet. It will thus be readily understood 20 that when the doors 6 are dropped to discharge the lading from the car, any lading which has a tendency to cake and adhere to the bent portion 8 of the doors, will be dislodged by the extension 9, 10, of 25 the side sheet 3.

In the drawings of this application, the edge of the lower flange of the reinforcing member 11 is shown in contact with the door 6 but this feature is not absolutely necessary, 30 and may be varied to suit any particular conditions or requirements.

Figs. 3 and 4 show modifications in the construction of the doors. In Fig. 3 the substantially upright portion of the door 6 is 35 shortened to some extent, and in Fig. 4 is shortened to a point at which the reinforcing member 11 is in close proximity to the door, both modifications resulting in a saving of material without in any way affecting the 40 efficiency of my invention.

I wish it to be understood that I do not desire to limit the scope of my invention to the forms of construction herein shown, as it will be apparent to those skilled in the art, 45 that many changes and modifications may be made, without departing from the spirit and scope of my invention, since

What I claim as new and desire to secure by Letters Patent is:—

50 1. In a dump car, the combination with a side sill of a side construction and a dump door, said dump door being hinged to said side construction above the side sill, said side construction being an extension of the side sheet adapted to meet the dump door intermediate its hinged and free edges.

55 2. In a dump car, the combination with a side sill of a dump door of substantially L section, a side construction to which said dump door is hinged above said sill, and an

extension to said side construction adapted to meet said door intermediate its hinged and free edges.

3. In a dump car, the combination of a side sill, a side sheet extending below said side sill, a dump door hinged to said side sheet above said side sill, the lower portion of said side sheet being adapted to meet said door intermediate its hinged and free edges. 70

4. In a dump car, the combination with a side sill of a hopper sheet, of an angular shaped door hinged above the side sill, the lower portion of said hopper sheet extending below said side sill and meeting the door intermediate its hinged and free edges. 75

5. In a dump car, the combination with a side sill of a hopper sheet having a reinforcing member at its lower edge, an angular shaped door hinged above the side sill, the lower edge of the hopper sheet and the reinforcing member meeting the door intermediate its hinged and free edges. 80

6. In a dump car, the combination with a side sill, of a hopper sheet having a reinforcing member secured to its lower portion, an angular shaped door having one side hinged above the side sill, the lower edge of the hopper sheet and the reinforcing member meeting the door intermediate its hinged and free edges. 85

7. In a dump car, the combination with a side sill and an angular shaped door hinged above said side sill, of a hopper sheet extending downwardly over one side of said door. 90

8. In a dump car, the combination with a side sill and an angular shaped door hinged above said side sill, of a hopper sheet extending downwardly over one side of said door, said hopper sheet being reinforced at its lower portion. 95

9. In a dump car, the combination with a side sill and an angular shaped door hinged above said side sill, of a hopper sheet overlapping one side of said door. 100

10. In a dump car, the combination with a side sill and an angular shaped door hinged above said side sill, of a hopper sheet overlapping one side of said door and a reinforcing member on the lower portion of said hopper sheet. 110

11. In a dump car, a side sill, a side sheet construction secured to and extending below said sill and an angular door hinged above said sill, said side sheet construction extending within the angle of said door. 120

12. In a dump car, a side sill, an angular dump door hinged above said side sill, a side sheet extending below said side sill, and a reinforcing member of channel form secured to the lower edge of the extension of said side sheet and adapted to meet said door intermediate its hinged and free edges. 125

13. In a dump car, the combination of a side sill, a door of substantially L section 130

hinged above said sill and a downward extension of the side sheet to meet the angular portion of said door, said side sheet being reinforced by a channel shaped member.

5 14. In a dump car, the combination of a side sill, a dump door hinged above said side sill and a side sheet extending below the side sill and substantially in contact with said door, said side sheet being reinforced 10 by a channel shaped member.

15 15. In a dump car, the combination of a side sheet extending below the side sill, the lower edge of said side sheet being substantially in contact with a drop door at a point intermediate its hinged and free edges when in closed position, said side sheet being reinforced at its lower edge by a channel shaped member, said drop door being hinged above said side sill.

20 16. In a dump car, the combination of a side sheet extending below the side sill, a reinforcing member of channel shape secured to the lower edge of the side sheet extension, said reinforcing member being substantially 25 in contact with the upper surface of the drop door, said drop door being hinged above said side sill.

30 17. In a dump car, a drop door of substantially L shape in cross section hinged above said side sill in combination with the side sheet extending from the top of the car to a point within the angle of the door formed by the L section, said side sheet at its lower edge being reinforced by a channel 35 shaped member.

40 18. In a dump car, the combination with an hopper sheet, of a side sill secured to said hopper sheet, an angular shaped door hinged at a point above the side sill, the hopper sheet meeting the door at a point intermediate its hinged and free edges, said hopper sheet being reinforced at its lower edge with a channel shaped member.

45 19. In a dump car, the combination with a hopper sheet, of a side sill secured to said hopper sheet, an angular shaped door, having one side hinged at a point above the side sill, the hopper sheet meeting the door at a point intermediate its hinged and free edges, 50 said hopper sheet being reinforced at its lower edge with a channel shaped member.

20. In a dump car, the combination with a

downwardly extending hopper sheet, of a side sill secured to said hopper sheet, an angular shaped door hinged at a point above 55 the side sill, the hopper sheet meeting the door at a point intermediate its hinged and free edges, said hopper sheet being reinforced at its lower edge with a channel shaped member. 60

21. In a dump car, the combination with a hopper sheet having a reinforcing member of channel form secured to its lower edge, of a side sill secured to said hopper sheet, and an angular shaped door hinged at a point above said side sill, the hopper sheet and reinforcing member meeting the door at a point intermediate its hinged and free edges. 65

22. In a dump car, the combination with a downwardly extending hopper sheet having a reinforcing member of channel form secured to its lower edge, of a side sill secured to said hopper sheet, and an angular shaped door having one side hinged at a point above said side sill, the hopper sheet and reinforcing member meeting the door at a point intermediate its hinged and free edges. 70

23. In a dump car, the combination with an angular shaped door hinged above the side sill of the door, of a hopper sheet extending substantially over one side of the door, said hopper sheet being reinforced at its lower edge with a channel shaped member. 85

24. In a dump car, the combination with an angular shaped door hinged above the side sill of the car, of a hopper sheet overlapping one side of said door, said hopper sheet being reinforced at its lower edge with a channel shaped member. 90

25. A dump car having side sills and L shaped doors hinged above said side sills. 95

26. A dump car having side sills and angular shaped doors hinged above said sills, said doors having their greatest length along their hinged edges.

In testimony whereof I affix my signature in presence of two witnesses.
